SAFETY RAZOR

Filed Feb. 16, 1929

Inventor.
John Menzak.
By Attorney.

UNITED STATES PATENT OFFICE

JOHN MENZAK, OF MANVILLE, NEW JERSEY

SAFETY RAZOR

Application filed February 16, 1929. Serial No. 340,362.

My invention comprises a simple and effective locking means adapted to an auto-strop razor known on the commercial market as "Valet" and shown, more particularly, in Letters Patent No. 1,022,726 dated April 9, 1912, being a type of safety razor in which the blade is pivoted so as to swing freely during the act of stropping the same but which, when in use for the shaving operation, is held against swinging by a pivoted frame constituting the guard which has heretofore been manually held upon the razor blade during the shaving act.

By my improvements, this guard member is locked relatively to the main frame to which the blade is pivoted so that when the guard is properly positioned over the cutting edge of the blade, said guard may be rigidly held mechanically to prevent accidental release of the pivoted blade, thus preventing possible serious injury to the user.

More particularly, the blade is carried by a pivoted member in a head adjustably secured to the end of the handle and the guard is pivoted to the adjustable head on a transverse axis parallel to the axis of the pivoted blade carrying part, and these features, common in this type of razor, are further distinguished by providing the handle with a notch or groove and the guard with a lug or projection which snaps into the notch or groove of the handle to form a detachable locking connection which may be readily moved to release the guard and blade when necessary for the stropping operation, but otherwise holds said guard as a protection to the cutting edge of the blade during the act of shaving.

My invention further comprises details of construction which, together with the features above mentioned, are more fully described hereinafter and pointed out in the claims.

Referring to the drawings: Fig. 1 is a plan view of a razor embodying my improvements; Fig. 2 is a longitudinal sectional view of the same; Fig. 3 is a perspective view showing the locking devices constituting my improvement; and Fig. 4 is an enlarged sec-

tional view corresponding to a portion of Fig. 2.

2 is the handle and is provided with a threaded end 3 which screws into the head frame 4, said head frame having forward projecting flanges 5 between which are provided rotary shafts 6 and 7 geared together at one end by pinions 8. The shaft 6 is provided with a downwardly extending socket portion 9 which is adapted to receive the blade 10 to so hold it that the cutting edge 11 thereof may swing freely with respect to the strop during the stropping operation. The blade is detachably connected with the socket portion 9, as is customary in a razor of this character.

12 is a pivoted comb-like guard having its lateral edges 13 bent to form sockets to engage the extreme ends of the cutting edge of the blade and to properly hold the blade in respect to the guard during the shaving operation. This pivoted guard 12 is hinged at 14 to side lugs 15 on the head frame 4. Furthermore, the guard 12 is provided with an upwardly extending arm 16 by which it can be oscillated about its pivot points 14. This upwardly projecting part 16 is provided with an opening 17 through which the shank of the handle 2 extends.

This handle shank is provided with an annular groove 18 and the upwardly projecting part 16 of the guard 12 is provided with a downwardly engaging edge 19 which is adapted to snap into the annular groove 18 of the handle shank, as is clearly shown in Fig. 2. In this manner, the guard is detachably locked in engaging position with the cutting edge of the blade and will hold this engagement during the shaving operation. To release the blade to allow it to swing for stopping purposes, it is only necessary to press forward upon the projecting part 16, with the result that its engaging part 19 is disengaged from the groove 18 and in turn causes the engaging parts 13 to release the lower end 11 of the blade.

The annular groove 18 insures proper engagement with the part 19 for any circumferential adjustment of the handle, but broadly considered, it is not necessary that the notch

or groove 18 shall extend completely around the shank of the handle, since it may be shaped in any manner so long as the part 19 is adapted to make a locking connection with the handle.

It will now be apparent that I have devised a novel and useful construction which embodies the features of advantage enumerated as desirable, and while I have in the present 10 instance shown and described the preferred embodiment thereof which has been found in practice to give satisfactory and reliable results, it is to be understood that I do not restrict myself to the details as the same are 15 susceptible of modification in various particulars, without departing from the spirit or scope of the invention.

Having thus described my invention, what I claim and desire to secure by Letters Patent is:

1. In a razor of the character described, the combination of a head frame having means for supporting a razor blade with provision for oscillation during stropping, a handle 20 secured to the head frame, a pivoted guard hinged to the head frame and having portions which engage the cutting edge of the blade for holding it against oscillation, and an extension from the guard provided with an engaging means for detachably locking it to the handle whereby the guard is held in engagement with the blade during the shaving operation, and wherein further, the handle is provided with a notched portion and in which 25 the engaging means of the guard is adapted to snap into the said notch when oscillated into engagement with the blade.

2. In a razor of the character described, the combination of a head frame having means for supporting a razor blade with provision for oscillation during stropping, a handle 30 rotatably secured to the head frame, a pivoted guard hinged to the head frame and having portions which engage the cutting edge of the blade for holding it against oscillation, and an extension from the guard provided with an engaging means for detachably locking it to the handle whereby the guard is held in engagement with the blade during the 35 shaving operation, and wherein further, the handle is provided with a shank having an annular notch-like groove and the extension from the guard is provided with an aperture through which the shank of the handle extends, said guard extension having its engaging means formed by a transverse edge 40 adapted to snap into the notch-like groove for all positions of rotary adjustment of the handle upon the head frame.

60 In testimony of which invention, I hereunto set my hand.

JOHN MENZAK.
